CLAIM

The ornamental design for a razor package label, as shown and described.

DESCRIPTION

FIG. 1 is a perspective view of a design for a razor package label of the present invention;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

In the drawings, the evenly-spaced broken line showing of portions of a razor package depicts environment and forms no part of the claim; the dash-dot-dash lines represent boundaries of the claimed design and form no part thereof.

1 Claim, 5 Drawing Sheets
